(57) **CLAIM**

We claim the ornamental design for a suspension adjuster for a motorcycle, as shown and described.

DESCRIPTION

FIG. 1 is a perspective view of a suspension adjuster for a motorcycle;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is a front view thereof positioned on a motorcycle. The broken lines shown illustrate portions of the suspension adjuster for a motorcycle and environment that form no part of the claimed design.
